UNITED STATES PATENT OFFICE.

HENRI PEGAITAZ, OF GRANGES, SWITZERLAND.

SURGICAL DILATOR.

Application filed July 13, 1920. Serial No. 396,011.

To all whom it may concern:

Be it known that I, HENRI PEGAITAZ, a citizen of the Swiss Confederation, and resident of Granges, Canton of Soleure, Switzerland, have invented a certain new and useful Improvement in Surgical Dilators, of which the following is a specification.

There is employed in surgery for the progressive dilation of certain organs of the human body a series of pointed rods of increasing diameter which are introduced successively into the organ to be dilated. These successive operations have the disadvantage of being often the occasion of the introduction of infectious germs within the organs under treatment.

Dilators of vegetable origin which are introduced in a dry and sterilized condition into the organs to be dilated and which swell in absorbing the secretions of the organs themselves cannot be employed for the dilation of large openings and in addition do not swell regularly. The swelling of the ends of the vegetable dilator, ends which from their transverse section are better suited to absorb the secretions above referred to increase more in diameter than the remainder of the dilator so that the extraction thereof is always painful.

The subject of the present invention is a surgical dilator by means of which it is possible to obtain a relatively very large diameter of opening by means of a single manipulation by the introduction of a single instrument which offers thus as compared with the rods referred to above, a great advantage.

The dilation obtained is regular and parallel and superior in effect to that obtained by means of vegetable dilators.

One embodiment of the dilator in accordance with the invention is illustrated in the annexed drawing, in which Figure 1 is a transverse sectional view of a dilator taken on line 1-1 of Fig. 2, the upper half of this view showing the prisms of the dilator extended and the lower half showing the same collapsed. Fig. 2 shows the dilator in longitudinal section in closed position and Fig. 3 is a similar section with the instrument open.

Referring to the drawing *a* is a rod about which are grouped sixteen prisms *b*, the bases *b'* of which have the form of a sector of a circle. These prisms are provided at each end with pivot members *c* provided

with pivotally mounted axes *b*² and connected by means of links *d* to pivot members *c'*, *c*² the one set being provided in a member *e* held at the end of the rod by means of a cap *e'* screwed over the end of the latter, the others in a sliding member *f* through which passes the end of the rod opposite that carrying the member *e* to which the segments are connected. These pivot members *c* may turn through a certain angle about their axes *b*².

The sliding member *f* is hollow and is threaded on its inner surface. It contains a conical spring *f'* which bears at its one end on the bottom of the sliding member and at the other on a plate *g* secured to the rod *a*. By means of a wing nut *h* the plate *g* may be caused to approach the bottom of the sliding member and compress the spring *f'*. In this position all the prisms touch one another and fit closely to the rod *a* as shown on the lower half of Figure 1 and in Figure 2. The instrument is introduced in this form into the opening in the organ to be dilated. The prisms are provided at each of their ends with a fixed pivot *i* through the medium of which they are connected in pairs by means of a link *l*.

When the spring *f'* is allowed to act on the plate *g* and cause the sliding member to approach the end of the rod to which the prisms are connected, these latter swing about the pivot members *c* and assume the position shown in the upper half of Fig. 1. While the prisms are separated from the rod the centres of the fixed pivots *i* are moved on two straight lines parallel to the plane of contact of the prisms when they touch the rod. When the instrument is in the position shown in Fig. 3 the sides of the prisms form a prism, the base of which is a regular octagon having as its longitudinal axis the axis of the rod.

The instrument is employed as follows:

After the nut *h* is screwed towards the bottom of the sliding member *f* in such manner as to compress the spring *f'* and causes all the prisms to approach the rod, the instrument is introduced within the opening to be dilated. The nut *h* is then unscrewed and the spring left free to act on the plate *g*. This causes the sliding member to approach slightly the end of the rod to which the prisms are connected and to separate the latter from the rod. The action of the spring will be proportionate to the resistance

of the tissues to be separated and to the time for which the process of dilation is to be continued. In cases of urgency to dilate the organ rapidly there will be screwed on 5 the rod after the nut *h* has been completely removed the ring *k* by means of which the rod may be pulled while the slide is held. The great advantage of the instrument described, which may be made of very small 10 dimensions, 6 to 8 mm., in diameter around the prisms, is the ease with which it can be sterilized before use. It produces a regular dilation and its extraction, since all the generatrices of its surface are parallel, is not 15 painful.

The members *c'* and *c²* may be formed, the first set in the material of the head the other in that of the sliding member. For certain purposes, as for intestinal dilations 20 for example, the spring, the plate *g* and the nut *h* might be removed from the sliding member, and then there may be fitted to the box *f* the sheath of a Bowden cable, the inner portion of which will be connected to 25 the rod *a*.

The instrument may be operated by means of the free end of the cable. This arrangement will permit the introduction of the instrument within organs which cannot be 30 easily reached.

The Bowden cable could also be replaced by a rigid tube within which a rod would move.

What I claim is:—

35 1. A surgical dilator comprising in combination a rod, a plurality of prisms grouped radially about said rod, the base of each of said prisms having its surface curved in the form of a sector of a circle, links connecting said prisms in pairs, arms connecting the prisms with the rod, a sliding member movable on the rod, and arms 40 connecting the prisms and said sliding member, substantially as and for the purpose set forth.

45 2. A surgical dilator comprising in combination a rod, a plurality of prisms grouped radially about said rod, the base of each of said prisms having its surface curved in the 50 form of a sector of a circle, links connecting

said prisms in pairs, arms connecting the prisms with said rod, a hollow sliding member movable on the rod, a plate mounted on the rod within the sliding member, a spring interposed between said plate and the base 55 of the sliding member, and arms connecting the prisms and said sliding member substantially as and for the purpose set forth.

3. A surgical dilator comprising in combination a rod, a plurality of prisms grouped radially about said rod, the base of each of 60 said prisms having its surface curved in the form of a sector of a circle, links connecting said prisms in pairs, arms connecting the prisms with said rod, a hollow sliding member 65 movable on said rod; a plate mounted on said rod within said sliding member, a spring interposed between said plate and the base of the sliding member, means for compressing said spring, and arms connecting the prisms and said sliding member, substantially as and for the purpose set forth.

4. A dilator including a rod provided at one end with a dome-shaped head, a slidable member mounted on said rod, links connected to said head and to said sliding member, radially movable members, connecting members swiveled to the radially movable members and pivotally connected to said links, means connecting the radially movable members in pairs for causing turning movement of the radially movable members during radial movement of said members, and means for moving said rod and slidable member relatively to one another 75 to cause radial movement of the radial movable members.

5. A dilator of the kind defined by claim 4 in which the radially movable members are of substantially prism shape, the base surface of each of said prisms being curved in the form of a segment of a curve.

6. A dilator of the kind defined by claim 4 in which the last mentioned means includes a resilient member cooperating with 90 said rod and slidable member.

In testimony whereof I have signed my name to this specification.

DR. HENRI PEGAITAZ.
